RAILWAY CAR CONSTRUCTION

Karl F. Nystrom, Milwaukee, Wis., assignor to
Chicago-Hutchins Corporation, Chicago, Ill., a
corporation of Delaware

Application April 10, 1933, Serial No. 665,414
Renewed February 22, 1938

5 Claims. (Cl. 105—409)

Current practices in railway car construction may be found in the Car Builder's Cyclopedic, 1931, published by Simmons-Boardman Publishing Company, 30 Church Street, New York, New York. Particular reference is made to pages 101 to 412 and pages 463 to 676.

In both freight and passenger car construction it is the common practice (see Fig. 545, page 359 and Fig. 1408, page 614) to first build the underframe, then mount the sideframes on the side sills, connect the tops of the sideframes by carlines and finally apply the roof and side sheathing.

This method, however, is very costly for it means that much of the drilling, riveting, and welding must be done on the car as it is being built, and often the men must work in very awkward positions. The method is also objectionable because the metal sheathing cannot be applied until after the sideframes and carlines have been built on the car, and consequently much time is wasted.

Primarily the object of the present invention is to reduce the cost of car construction by eliminating all of the framework. This is accomplished by building the car body from a plurality of sheet metal sections which are provided with inwardly extending reinforcing flanges sufficient in size and number to give the body the necessary strength.

Other objects of this invention include the use of standard-sized mill sheets for the sheet metal sections, standard-sized veneer sheets for the inside lining, and an arrangement of the flooring whereby all waste is avoided; shaping the car to reduce wind resistance to a minimum; providing a floor construction that protects the side joints against ingress of moisture and which enables the floor to be partly or wholly renewed without disturbing any of the interior finish; providing a car body which facilitates repairs in case of an accident and reduces the area over which the damage is likely to spread; providing novel arrangements of the longitudinal and latitudinal running boards and the side and end ladders, and a method of constructing a car which embodies the above advantages and furthermore permits the greater part of fabrication to be done before assembly where the work can be done far more expediently.

Further and other objects and advantages of the invention will become apparent as the disclosure proceeds and the description is read in conjunction with the accompanying drawings, 55 in which

Fig. 1 is a fragmentary, side elevational view of a box car made in accordance with the present invention;

Fig. 2 is a sectional view taken on the line 2—2 of Fig. 4, looking down on the flooring; 5

Fig. 3 is an enlarged detail section of one of the corners;

Fig. 4 is a vertical, sectional view taken on the line 4—4 of Fig. 5;

Fig. 5 is a sectional view taken on the line 5—5 10 of Fig. 4 looking toward the end wall of the car, a part of the interior finish being broken away to disclose the structure behind;

Fig. 6 is an enlarged detail section showing the mating of the end sheet with the roof; 15

Fig. 7 is an enlarged detail section showing the junction between the car body and the side sill, the section being taken on the line 7—7 of Fig. 2;

Fig. 8 is an enlarged detail section through the 20 roof, the section being taken on the line 8—8 of Fig. 7;

Fig. 9 is an enlarged detail sectional view of the upper right hand portion of the car, taken through one of the side plate pans;

Fig. 10 is a sectional view taken on the line 10—10 of Fig. 5;

Fig. 11 is a sectional view taken on the line 11—11 of Fig. 4.

While the invention has been illustrated as applied to a box car, it will be understood that this is for the purpose of disclosure only, for the invention is equally applicable to other types of railway cars.

Also the details of construction are merely illustrative of the invention and should not be construed as imposing limitations upon the appended claims except as may be required by the prior art.

The car chosen to illustrate the invention is a 40 box car having an underframe 20 mounted on trucks 21. The car body, generally designated 22, comprises sides 23 and 24, ends 25 and 26, and a roof 27 upon which longitudinal and latitudinal running boards 28 and 29 respectively, are 45 mounted. Side and end ladders 30 and 31 are mounted at the ends of the car according to A. R. A. specifications.

Underframe

50

In building a car according to this invention, the underframe 20 is first fabricated, if not integrally cast, and is then mounted on the car trucks.

In the present embodiment of the invention, 55

the underframe is fabricated and comprises standard A. R. A. center sills 32, side sills 33, end sills 34, body bolsters 35, braces 36, and floor beams 37, all riveted and/or welded to form a rigid structure.

The side sills 33 (best shown in Fig. 7) may be termed angle or channel bars and are placed with their apexes pointing upwardly and outwardly; the outside legs 39 of the side sills 10 project downwardly and then inwardly with a smoothly curved bend 40. Preferably the leg is curved according to the formula $Y=2 \log X$ with the origin of the curve at 41.

The upper legs 42 of the side sills extend horizontally inwardly a certain distance, then downwardly as shown at 43 and then inwardly to form shoulders 44. The outside floor boards of the floor 38 rest upon the shoulders 44 and abut the downwardly extending portions 43. Since the 20 depth of the offset is approximately the thickness of the floor, moisture within the car will drain between the flooring and the side sill rather than through the joint between the car body and the side sill. This is particularly desirable because it avoids the collection of moisture at the 25 base of the car sides.

It is common practice to lay the floor boards crosswise between the center sills and the side sills but this practice results in unnecessary 30 waste because the floor boards do not come in nine foot lengths which is the span between the side sills of a standard box car. Floor boards, however, do come in fourteen foot length and since a standard car is forty feet six inches 35 in length, three of such standard length floor boards can be used with a minimum amount of waste.

As shown, the floor boards are tongue and 40 grooved and rest upon end sills 34, bolsters 35, floor beams 37, center sills 32 and side sills 33. The boards are individually bolted to the end sills 34 as shown in Fig. 2 and to the various cross members of the underframe. Although the flooring may be laid on the underframe before applying the car ends 25 and 26 and the sides 23 and 45 24, it is preferably laid later to facilitate the welding of the sides and ends to the underframe.

After the underframe has been set up and pieced together, the usual striking castings 45 50 and bolster fillers 46, along with draft gears, couplers, etc. are applied and the car is then mounted on the trucks 21.

Sides

55 While the underframe is being made, another part of the shop may be at work in fabricating the car sides. In general, the car sides 23 and 24 are composed of a plurality of sheet metal sections 47 provided with inwardly extending top and bottom flanges 48 and 49, respectively, and side flanges 50 and 51, respectively, the latter being bent inwardly again at 52 parallel to the face of the section. The end sections 53 do not have a flange corresponding to the flange 52, but are otherwise identical with the other sections.

All of the sections with the exception of the corner sections 53 are made by taking standard-sized mill sheets of 42" width and drawing out 70 the top, bottom and side flanges to form what may be termed a pan. All flanges of the pan may be 3 1/8" deep; and the flange 52 may be 2" in width, as these dimensions have been found to give the sections the desired strength. The 75 end sections 53 are made from 40" plate also of

standard size; and the top, bottom and side flanges are all 3 1/8".

All of the sections are made of 1/8" steel plate which in combination with the reinforcing flanges provides adequate strength to resist the 5 outward pressure of the lading and furnish support for the superstructure.

The sections may be bolted together and then welded along the inside and outside of the mating flanges to provide a unitary structure with 10 inwardly extending reinforcing flanges.

Since the door in a box car is ordinarily in the center of the car, each of the sides will be made up of two units fabricated as described above. These units are mounted on the underframe and then welded, as indicated at 54 and 55, leaving a space for the door, which is not shown. The door also is made up of two or more panels similar to the ones used in the sides. Preferably the tops and bottoms of the side 20 panels or sections 47 and 53 are slightly curved as indicated at 56 and 57, respectively, to blend with the roof and side sill curves.

After the sides 23 and 24 are mounted on the underframe and welded in place, furring or nail- 25 ing strips 58 are secured to the inside of the flanges 50 by bolts 59 to provide a means for fastening the interior finish to the side walls.

Ends

30 The ends 25 and 26 are preferably made in one piece from 1/4" steel plate, corrugated as shown in the drawings. The tops of the ends are flanged inwardly as shown at 60 and then downwardly as shown at 61, the latter flanges being 35 adapted to mate with the adjacent flanges of the roof and be secured to the roof by welding. The bottom of the ends are provided with flanges 62 which rest upon the end sills and are welded to said sills on both the inside and outside of the 40 flange. Side flanges 63 and 64 provided with inwardly turned portions 65 and 66 are welded to the mating flanges of the corner sections 53 of the sides 23 and 24, respectively.

Resting inside each end sheet on the flange 62 45 is a transverse furring strip 67 rabbeted at 68 to receive the interior finish. The furring strip 67 is secured to the flange 62 by bolts 69, the heads of which are spot-welded to the flange.

Other transverse furring strips 70, 71 and 72 are secured to the inside of the end sheets 25 50 and 26 by bolts 73 having their heads spot-welded to the sheet.

The furring strip 72 is, of course, curved to 55 conform with the shape of the roof and has a rabbet 74 to receive the interior finish.

Roof

The roof also is made up of a plurality of sheet metal sections comprising center sections 74, 60 intermediate sections 75 and side plate sections 76. The sections have inwardly projecting reinforcing flanges 77 extending completely around the marginal edges of the sections. The tops of the sections are curved according to the equation $Y=8 \log X$, the origin of the curve being indicated at 78.

The center sections 74 are made from No. 16 gauge steel plate, and the intermediate sections 75 from No. 15 gauge steel plate, both plates 70 having a width of 32", which is a standard mill size. The side sections 76 are made from No. 7 gauge steel plate, which is considerably heavier than the plate used for either the center sections 74, intermediate sections 75, or side sections 47 75

and 53. The width of the plate is 18" which is also a standard mill size.

The center and intermediate sections 74 and 75, in addition to being the same width are also 5 the same length, as indicated in Fig. 1. The side plate sections 76, however, are twice as long as either the center or intermediate sections 74 and 75 (Fig. 1). The purpose of this arrangement is to cause the heavier gauge metal in the 10 side plate sections to oppose any tendency of the center and intermediate pans to buckle along the latitudinal flanges. The heavier metal of the side plate sections is also desirable because these sections act as a longitudinal beam and 15 strengthen the center portion of the car which is being constantly subjected to vertical stresses.

By making the roof into center, intermediate, and side plate sections, the former two may be made of comparatively light metal, because of 20 the small proportion of the total load which they carry, while the side plate sections are made of heavier metal to withstand the greater stresses to which they are subjected.

Furring strips 79 are secured by bolts 80 along 25 one longitudinal and one latitudinal flange 77 of each section. The furring is, of course, curved to conform with the curvature of the roof.

The roof is fabricated by taking the center, intermediate, and side plate sections and bolting 30 together the mating flanges. The sections may then be welded together both on the inside and outside of the flanges to provide a unitary roof structure, which is self-supporting and requires no supplemental framework.

35 After all the sections have been welded together both longitudinally and latitudinally, the furring strips 79 are applied to the flanges 77 and are secured in place by the bolts 80. The side plate sections 76 have straight edge furring 81 which constitute continuations of the side furring 58.

After the roof sections have been welded together, metal saddles 82, which support the running board sections, are welded along the top seam. The saddles are in the form of U-brackets 45 provided with outwardly extending flanges 83 upon which the running board 28 rests. The running board may then be applied to the car roof or may be later applied when the roof has been assembled on the car.

50 The latitudinal running board brackets 84 are also welded on the car roof before the roof is mounted on the car.

The car roof, which is now completely welded 55 and is provided with the necessary furring and with the necessary running board brackets and saddles may now be lifted by a suitable hoist and placed on the car sides and ends. The top flanges 48 of the side sections are then welded to the 60 bottom flanges of the side plate sections and the end flanges of the roof are welded to the downwardly extending flanges 61 of the car ends to make the entire car body a unitary structure.

Interior finish

65 The interior finish comprises base boards 85, side plates 86, side lining 87, end lining 88 and 89, and ceiling lining 90.

The base boards extend completely around the 70 interior of the car, the side base boards resting upon the raised horizontal portion of the side sill legs 42. The base boards are secured in place by fastening them to the side furring 58.

The side plates 86 are irregularly shaped 75 wooden strips (see Fig. 9) the main outline of

which includes the dotted line portion indicated at 91. The side plates, however, are notched at 92 to accommodate the latitudinal flanges and furring of the side plate sections. The side plates are secured in place by fastening them 5 to the side plate furring and to the lower longitudinal furring of the intermediate sections of the roof. The upper edges of the side plates are rabbeted at 93 to accommodate the ceiling lining 90.

The side lining 87 comprises a plurality of veneer sheets which are but slightly smaller than the standard sized sheets. The sheets are trimmed to the desired size and then fastened to the furring that is provided.

15 The end lining is also veneer and is secured to the transverse furring strips 70 and 71. The upper end lining 89 is curved to conform to the roof and is secured to the transverse furring strips 71 and 72. The ceiling sheets 90 which are also veneer extend from the center of the roof to the side plates and are pressed into conformity with the roof furring and then secured in place to the furring. A batten strip 94 covers 20 the joint between the two halves of the ceiling 25 lining.

One feature of this invention is the fact that the side, end and ceiling linings may be removed independently of one another. This is accomplished by forming the corners as shown in Fig. 3 30 with the end lining 88 seated within the rabbeted edge 74 of the furring 72. In order that the joint will be weatherproof and waterproof, a galvanized iron strip 95 is fitted into the corner so that a slight spreading of the side and end sheets will 35 not permit moisture to enter the car.

In a similar manner, the joint between the roof and the car end is provided with an iron strip 96, and serves the same function.

Longitudinal running board

The running board 28 is made in four sections, the end sections of which are supported by brackets 97 which are welded to the car ends. Each section comprises three boards 98 which are united at their ends by U-shaped metal strips 99 embedded in the wood. The boards are also united at their mid-sections by a wooden saddle 100 to which the boards are suitably secured and which is shaped at the bottom to conform to the curvature of the roof.

50 Therefore, to apply the running boards to the roof, it is only necessary to put them in place with their ends resting on the metal saddles 82 and bolt them to the saddles by bolts 101, the 55 metal saddles 82 having already been welded to the car roof.

Latitudinal running board

The latitudinal running board 29 comprises a 60 plurality of transverse boards 102 which are secured to the angle members 103. The brackets 84 which are welded to the roof before it is mounted on the car enable the latitudinal running board to be fastened in place by bolts 104 65 which pass through downwardly extending flanges provided on the angle members 103.

Side and end ladders

Side and end ladders ordinarily have their 70 rungs fastened to the sides by bolts which pass clear through the body. Consequently, when a rung is broken it is necessary to unload the car and disturb part of the interior finish in order to remove the bolts holding the broken rung.

In the present invention, this objectionable practice is obviated by having the sides 105 of the ladders 30 and 31 provided with offset portions 106 to which the rungs 107 may be fastened. The rivet 108 or other fastening means employed for securing the rung to the side need only pass through the rung and the side. It does not enter the car body. Therefore, whenever a rung is broken, it may be quickly replaced.

10 The side and end ladders 30 and 31, respectively, are secured to the car body by welding.

A railway car made in accordance with this invention is strong, durable and in case of accident may be easily repaired by replacing the 15 damaged sections. The car is much cheaper to build than those in common use; presents a smooth exterior finish, which in combination with the shaping of the car reduces wind resistance to a minimum; and can be constructed 20 in less time due to the fact that the several components of the car may be made in different parts of the shop and then assembled.

What I claim as my invention is:

1. In a railway car, the combination with an 25 underframe of a car body superstructure supported thereon, the sides and roof of which comprise a plurality of sheet metal panned sections welded together to form a unitary structure with a smooth exterior surface and with longitudinal 30 and lateral inwardly extending flanges welded to each other forming in abutting sections a network of reinforcements, the corresponding flanges of adjacent sections being continuous with each other and sufficient to give the car body adequate 35 trussing strength without the necessity of separate supporting frame work in the superstructure, there being at least a plurality of laterally abutting sections between the longitudinal roof center and each side wall of the car.

40 2. In a railway car, the combination with an underframe of a car body superstructure supported thereon, comprising a plurality of sheet metal panned sections welded together to form a unitary structure with a smooth exterior finish, 45 the sections forming the sides of the car having vertical flanges for resisting laterally directed forces and the sections forming the roof of the car having series of parallel flanges longitudinally and latitudinally of the car, the corresponding 50 flanges of adjacent sections being continuous with each other and welded together so that when all sections, side and roof, have been united, the said flanges will afford adequate trussing strength to enable said superstructure to resist buff and 55 draft shocks and the pressure of lading without supplemental frame work, there being at least a plurality of laterally abutting sections between

the longitudinal roof center and each side wall of the car.

3. A railway car body superstructure comprising a plurality of sheet metal panned sections secured together to form a unitary structure, said sections including separate side, side plate and roof sections, inwardly directed longitudinal and lateral flanges on the sections forming stiffening elements for resisting the usual body strains, the corresponding flanges of adjacent sections being continuous with each other, said flanges being sufficient in number and dimensions to avoid the necessity of supplemental frame work, and including a plurality of parallel longitudinal flanges in said roof sections, said side plate sections being sufficient in strength to form the top cord of a truss.

4. A railway car body superstructure comprising a plurality of sheet metal panned sections secured together to form a unitary structure, 20 said sections including separate side, side plate and roof sections, inwardly directed longitudinal and lateral flanges on the sections forming stiffening elements for resisting the usual body strains, the corresponding flanges of adjacent 25 sections being continuous with each other, said flanges being sufficient in number and dimensions to avoid the necessity of supplemental frame work in the superstructure, and including a plurality of parallel longitudinal flanges in said roof 30 sections, the metal of which said side plate sections are made being of heavier gauge than the metal in the roof sections.

5. In a railway car, the combination with an underframe, of a car body superstructure supported thereon, the sides and roof of which comprise a plurality of sheet metal panned sections welded together to form a unitary structure with a smooth exterior surface and with longitudinal and laterally inwardly extending flanges welded to each other forming in abutting sections a network of reinforcements, the corresponding flanges of adjacent sections being continuous with each other and sufficient to give the car body adequate trussing strength without the necessity of separate supporting frame work in the superstructure, there being at least a plurality of laterally abutting sections between the longitudinal roof center and each side wall of the car, furring secured to the flanges of said panned sections, and interior finish attached to the furring for covering said flanges, said finish comprising side lining plates, lining sheets beneath said side lining plates, and a flat ceiling sheet pressed into conformity with the curvature of the roof abutting against said side lining plates and secured to the roof furring.

KARL F. NYSTROM.
